(57) **CLAIM**

The ornamental design for a heel pattern for shoe, as shown and described.

DESCRIPTION

FIG. 1 is a perspective view of an embodiment of a heel pattern for a shoe;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line portions shown in the figures are for illustrative purposes only and form no part of the claimed design. The figures include textured portions, which are designed to show a stitched fabric of the embodiment's design. The heel pattern of the embodiment shown in the figures depict a different shading contrast than the remaining portions thereof. Colors form no part of the claimed design.

1 Claim, 6 Drawing Sheets
